EARTH AUGER

John C. Jaques, Denison, Tex.

Application February 1, 1946, Serial No. 644,684

3 Claims. (Cl. 255—19)

1

This invention relates to new and useful improvements in earth augers.

One object of the invention is to provide an improved earth boring unit wherein all of the elements, including the auger, driving and control means and power means, are mounted on a single base or skid frame, thus providing a unitary structure which may be placed on the bed of a truck or other vehicle and extended therefrom for earth boring.

A further object of the invention is to provide an earth auger wherein the boring tool may be raised and lowered by fluid-actuated means under manual control, whereby the tool may be fed to the work and the boring regulated and fully controlled.

Another object of the invention is to provide an earth auger wherein the boring elements are combined in a unit including, the boring shaft and auger, the mast in which the shaft is housed, the driving mechanism for the shaft and a support for the foregoing and the power plant, all mounted upon a frame to be mounted on a vehicle, whereby the mast may be swung in a vertical arc to raise and adjust the same to the desired upright position and also whereby, the mast may be swung in a transverse arc to adjust the same and compensate a transverse inclination when the wheels of the vehicle are resting upon uneven ground.

Still another object of the invention is to provide an improved earth boring unit having hydraulic means for adjusting its boring mast together with control means conveniently arranged adjacent the auger, whereby the entire operation may be readily and efficiently handled.

A still further object of the invention is to provide an improved driving and supporting means for the boring shaft and its mast connected at one end with a power shaft and adjustably supported at its opposite end, whereby said means may be swung in an arc transversely of said power shaft.

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is a plan view of an earth boring unit constructed in accordance with the invention, portions being shown in section,

Fig. 2 is a side elevation of the same,

2

Fig. 3 is an elevation of the opposite side of the unit.

Fig. 4 is a rear elevation of a truck having the unit mounted thereon,

Fig. 5 is a vertical sectional view of the mast and a portion of its driving mechanism,

Fig. 6 is an isometrical view of the rear end of a truck having the unit mounted thereon,

Fig. 7 is an isometrical view of the unit, and

Fig. 8 is a diagrammatical view of the hydraulic system.

In the drawings, the numeral 10 designates an elongate generally rectangular base frame which is preferably channel-shaped in cross-section.

15 The frame includes a central beam 11 extending longitudinally thereof and a transverse bolster 12 secured to one side of the beam 11 and one side of the frame. This bolster is set back from the rear end of the frame. The bottom of the frame is flat and is thus of the skid type whereby it may be slid on a flat surface. All the elements of the apparatus are carried by this frame, thus producing a unitary structure. The frame may be mounted on a truck, trailer, or any other form 20 of vehicle, and for the purposes of illustration, the unit is shown as mounted on a motor truck of the flat bed type. The frame 10 is secured on the flat bed 13 by means of fastenings 14 or in any other suitable manner and the flat bed 25 is carried upon the usual frame 15 supported on rear wheels 16. While the frame 10 is generally rectangular, it has a rearward rectangular extension 17 at one side, as is best shown in Figs. 1 and 5.

30 In addition to the frame, the unit includes, in general, an elongate tubular drilling guide cylinder A, in which a boring shaft B, square in cross-section, is adapted to rotate and to move vertically. This shaft extends through a gear housing C and has an earth auger or drilling bit D on its lower end. The elements in the gear housing which drive the shaft and which will be hereinafter described, are driven from a transmission casing E in which the forward end of the

35 driven shaft F is connected. The rear end of the shaft F is connected with a suitable clutch G which, in turn, is connected by a clutch shaft H with a standard transmission I. The transmission I is connected by a drive shaft J with a power plant K, which includes an internal combustion engine and which is not illustrated in detail because such plants may be purchased in the open market.

40 As is best shown in Figs. 1, 2 and 6, the transmission housing E is provided with a tubular

shank 18 which is bolted to a sleeve 19. This sleeve is rotatably confined in a bearing box 20 by means of collars 21 made integral with the sleeve and engaging said box. The box is rigidly mounted on a standard 22 carried by a transverse base plate 23 which, in turn, is bolted to one side of the frame and the beam 11. The driven shaft F extends through the sleeve and the shank and has fastened on its rear end, a beveled pinion 24 which engages a ring gear 25 mounted in the housing. The rear end of the housing is provided with a trunnion 26 which is rotatably confined in a bearing bracket 27. This bearing bracket is carried by an upright transverse standard 28 which may be formed integral with a mounting plate 29 secured on the rearwardly projecting end of the main frame 10. By means of the construction which has been described, the housing E may be rotated or swung in an arc around the longitudinal axis of the shaft F.

As is best shown in Fig. 5, the ring gear is bolted around a cylindrical hub block 30 which is provided at each end with hubs 31 mounted in ball bearings 32 seated in the housing, said housing being sectional, as is the common practice. As its inner side, the housing is provided with a collar 33 in which one end of a sleeve 34 is secured. This sleeve has a snug rotating fit in a jacket 35 which carries a stuffing box 36 surrounding the sleeve adjacent the collar. The opposite end of the sleeve is provided with an outwardly directed annular flange 37 which is rotatably confined between a flange 38 on the end of the jacket and a flange 39 carried on the outer end of a collar 40 secured to the gear housing C. It is obvious that when the gear housing is swung forwardly or rearwardly, the collar 40 and the jacket 35 will rotate upon the sleeve 34; also that the jacket 35 may rotate on the sleeve when the mast A is tilted forwardly or rearwardly.

On the outer side of the gear housing C, a trunnion 41 is provided and this trunnion is rotatably confined in a bearing box 42 (Figs. 2, 4 and 7), which is carried by an angular hanger 43 pivoted to the lower end of the piston rod 45 of a vertical hydraulic cylinder 44. The upper end of the piston rod is pivoted to a lug 46 depending from an overhanging bracket 47, made integral with the upper end of a standard 48, secured to the rear end of the frame 10 above the bolster 12. The rear face of the standard is flat and the bearing box 42 is slidably confined on the lower end of this face by stud bolts 49. By supplying a suitable pressure fluid to the cylinder, the piston rod is raised and lowered, whereby the hanger 43 is moved upwardly and downwardly and the gear housing C thus adjusted in a vertical arc transversely of the frame. The elements which have been described permits the gear housing and drilling guide cylinder to be swung from the upright position shown in Figs. 2, 3, 4 and 6 to the inclined position shown in Fig. 7. The drilling guide cylinder is swung to the position in Fig. 7 when the unit is transported from place to place and rests upon a prop 50 carried by the main frame. Since the unit will usually be supported on a vehicle and since the ground may not be level, upon which the wheels 16 rest, it will be necessary to adjust the drilling guide cylinder in vertical arcs at right angles to each other in order to bore a straight hole. The structure which has been described will permit these adjustments.

The drilling guide cylinder A includes an elongate cylinder 51 closed at its upper end by a cap 52. The lower end of the cylinder 51 is screwed into a flanged cylindrical head 53 which is carried in an annular socket 54 formed on the upper end of a spider 55. The lower end of the head 53 carries a stuffing box 56. The spider is suitably secured on a circular base plate 57 formed integral with the upper end of the housing C, which latter is of the sectional type.

Within the housing, a rotatable hub block 58 is vertically mounted. A tubular shank 58 extends upwardly from this block and has a rotating bearing in the bore of the head 53 and is surrounded by the stuffing box 56, as is best shown in Fig. 5. Just above the block 57, the shank is confined in a ball bearing element 59 secured in the housing C. A tubular spindle 60 depends from the hub block 57 through the bottom of the housing C and is surrounded by a ball bearing element 62 carried in the housing. A stuffing box 62 is carried by the lower end of the spindle. The square shaft B has a snug sliding fit in a complementary bore 63 which extends through the hub block 57, the shank 58 and the spindle 60. For rotating the hub block, a horizontal ring gear 64 is fastened thereon and driven by a beveled pinion 65 fastened on the end of a countershaft 66 which extends through the sleeve 34 and is secured in the hub block 30 of the transmission. The hub block is rotated, whereby the shaft B is rotated, but said shaft is free to move vertically while rotating.

One of the novel features of the invention is the provision of hydraulic means for manipulating the drilling guide cylinder. The cylinder 44 for vertically adjusting the housing C has been described. For swinging the drilling guide cylinder A, a hydraulic cylinder 67 is provided. This cylinder has its forward end pivoted in a bracket 68 carried by a cross beam 69 forming part of the main frame 10. This cylinder is provided with a piston rod 70 and is disposed at an inclination so that its upper and rear end may be pivoted between ears 71 carried by a clamp 72 secured around the base of the cylinder 51 just above the head 53, (Fig. 2). By energizing the cylinder 67, it is obvious that the drilling guide cylinder may be swung to its various positions. For hydraulically raising and lowering, as well as forcing the shaft B downwardly, a tubular piston 73 is mounted to slide vertically in the cylinder 51. This piston is provided with rings 74 (Fig. 5) which engage the inner wall of the cylinder. The upper end of the shaft B has a reduced shank 75 extending into the piston and carrying an upstanding axial stud 76. The upper end of the shank 75 bears against an internal flange 77. The stud 76 is screw-threaded and the cone 78 of a roller bearing is fastened thereon by a nut 79. The outer race 80 of the bearing is secured to the inner wall of the piston and the shaft B is thus rotatably supported.

A right angular fluid conducting pipe 81 enters the cap 52 to supply and exhaust pressure fluid above the piston. A similar pipe 82 enters the head 53 just above the shank 58 for supplying and exhausting pressure fluid below the piston. For supplying a fluid, such as oil, under pressure, a centrifugal pump 83 is mounted on the base plate 23 below the bearing box 20.

This pump is supplied with oil from a reservoir 84 by means of a pipe 85. The reservoir is suitably supported on a bracket 86 carried by the main frame. The pump is connected with a T

87 by means of an outlet nipple 88. A pressure fluid supply pipe 89 extends rearwardly from the T. The pipe 89 is connected by an elbow 94 with the inlet 95 of an operating valve 91, the outlet of which is connected with the inlet of a second valve by means of a nipple 96. The outlet of the valve 92 is connected by means of a nipple 97 with the inlet of a third valve 93, the outlet of which is connected with a return pipe 98. The return pipe 98 extends under the frame and along the beam 11 to the reservoir (Fig. 3) whereby the fluid is returned to the reservoir. The forward end of the T 87 is connected with a pressure relief valve 99 and a flexible by-pass conductor 99 connects the valve with a return pipe 99.

The valves 91, 92 and 93 respectively are of duplicate construction and may be purchased in the open market. Each valve is provided with a plunger 100 pivoted to an operating lever 101. These valves are of the type that the pressure will flow therethrough from the elbow 94 to the return pipe 98 at all times, irrespective of the positions of the levers. Each valve is provided with an inlet and an outlet so that upon adjustment of the lever, a portion of the supply fluid will be discharged from the valve, while in another position, pressure fluid may enter the valve and escape therefrom with the pressure fluid which is being supplied and exhausted therefrom.

The valve system is diagrammatically illustrated in Fig. 8. The valve 91 is provided with a pair of flow connections 102 and 103. The connection 103 communicates with the pipe 81 at the top of the drilling guide cylinder A by means of a flexible conductor or hose 104; while a similar hose 105 is attached to the connection 102 and the elbow 82 of the head 53. When the lever 101 of the valve 91 is pulled rearwardly, pressure fluid is supplied to the hose 104 and thus delivered to the cylinder 51 of the mast A on top of the piston 73 whereby the shaft B is forced downwardly. Oil in the cylinder below the piston is exhausted by way of the hose 105 to the valve 91. By manipulating the lever of the valve 91, the desired fluid pressure may be imposed upon the rotating shaft B.

The valve 92 has connections 106 and 107 similar to the connections of the valve 91. A hose 108 extends from the connection 106 to the top of the cylinder 44 while a hose 109 extends from the bottom of said cylinder to the connection 107. By swinging the lever of the valve 92, the piston and the cylinder 44 may be raised or lowered. The valve 93 has connections 110 and 111. The connection 110 is attached to a hose 112 which is in turn connected to the upper end of the cylinder 67; while a hose 113 leads from the bottom of the cylinder 67 to the connection 111. It is pointed out that the three valves, being mounted on the plate 28, which extends from the rear end of the frame 10, as is clearly shown in Fig. 6, the operator standing by these valves may readily and easily adjust the various hydraulic elements and control the boring.

The transmission shaft H being connected with the shaft F (Figs. 1, 2 and 3) by means of the transmission clutch G, operation of said clutch will control the transmission of power to the boring shaft B. For operating the clutch G, a bell crank lever 114 is pivoted on the side of an upright web plate 115 mounted on the plate 23. The upper end of this lever is pivotally connected to a link 116 which, in turn, is pivoted to the

operating arm 117 of the clutch. Adjacent the return pipe 98, a clutch lever 118 is pivoted on a bracket 119 mounted on the plate 28. This lever is connected with the bell crank lever 114 by means of a pitman 120. By shifting the lever 118, the clutch G is operated. A similar lever 121 is pivoted on a bracket 122 mounted on the plate 28 adjacent the bracket 119. This lever is connected by means of a pitman 122 with the operating crank 123 of the clutch of the power plant K.

In operating the apparatus, it will be assumed that the drilling guide cylinder A is resting in its inclined position and supported on the prop 50, as is shown in Fig. 7. By operating the lever 101 of the valve 93, pressure fluid is supplied by way of the pipe 113 to the lower end of the cylinder 67, whereby the piston 70 is moved rearwardly to swing the drilling guide cylinder to an upright position. When the drilling guide cylinder reaches this position, the valve lever is swung to a neutral position, whereby the pressure on each side of the piston in the cylinder 67 is equalized, thus maintaining the drilling guide cylinder in an upright position. In order to aid in bringing the drilling guide cylinder to a true vertical position, a pivoted arrow 125 is suspended on the rear side of the clamp 72 and a second arrow 126 is pivoted on the inner side of said clamp at right angles to the arrow 125. Center pins 127 are provided, and when the arrows register with these pins, the drilling guide cylinder is in a true vertical position.

If the ground upon which the wheels 16 are resting is uneven, which is frequently the case, it will be necessary to adjust the drilling guide cylinder so that a vertical hole may be bored. For effecting an adjustment transversely of the main frame, the valve 92 is operated to actuate the piston 45 of the cylinder 44, whereby the hanger 42 is raised and lowered and the adjustment obtained. To adjust the drilling guide cylinder longitudinally of the frame, the valve 93 is again operated for this purpose. During this adjusting period, the valve 91 is in a neutral position so that pressure on each side of the piston 73 of the mast cylinder 51 is equalized, and the lever 121 of the clutch arm 123 is in a neutral position so that power is not being transmitted from the power plant K. The operator selects his rate of transmission and shifts the lever of the transmission I accordingly. The clutch G is in a neutral position and therefore, power is not transmitted to the shaft F.

The operator now manipulates the lever 101 of the valve 91 to lower the shaft B so that the auger engages the ground. He then shifts the lever 118 whereby the clutch G is engaged and rotation is imparted to the shaft B and auger D. When the proper depth has been reached, the operator actuates the lever 118 to disengage the clutch and interrupt the transmission of motion to the boring shaft. He then operates the valve 91 to raise the auger and shaft. During the boring period, fluid pressure is maintained on top of the piston 73 sufficient to force the auger downwardly as it is rotated.

A panel board 128 is mounted on a bracket 129 secured to the standard 28 and carries a starter button 130, as well as other power plant instruments which are not shown. The starter button is connected by a plunger 131 with the starter of the power plant. It is pointed out that the operator standing behind the valves and levers has the apparatus under full control and does not

have to change his position during any of the operations.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. In an earth auger, the combination of a portable support, an elongate drilling guide cylinder, a drilling shaft movable longitudinally in the cylinder and having a bit at its lower end, a gear case pivotally carried on the support, a torque tube extending from said case, a gear housing connected to the extended end of said tube, a trunnion connected to said housing for swinging the housing and tube in a vertical arc, gearing in the gear case, gearing in the housing, a shaft in the tube operably connected with both gearings, the drilling shaft being rotatably connected with the gearing in the housing, an upright standard carried on the rear of the support adjacent the trunnion, said standard having a flat rearward face, a hanger having a forwardly directed flat face slideably abutting the face on the standard, said hanger receiving the trunnion on the gear housing, a hydraulic cylinder vertically secured to said standard and having a piston, a piston rod connected to the piston and extending from the cylinder, the extending end of the rod being pivotally connected with the hanger so as to move the hanger upwardly and downwardly to swing the housing and the guide cylinder in a vertical arc.

2. In an earth auger, the combination of a portable support, a power plant mounted on the support, a gear case having a driven shaft connecting with the power plant, a sleeve enclosing the driven shaft and rotatably mounted on the support, said sleeve being connected to the gear case, a trunnion connected to the opposite side of the gear case, the case being supported on the sleeve and trunnion so as to be rotatable in a plane transverse to the longitudinal axis of the driven shaft, a torque tube extending from said case, a gear housing connected to the extended end of said tube, a hanger connected to the opposite side of said housing, a hydraulic cylinder vertically mounted on the support connected to the hanger for raising and lowering the hanger for swinging the housing and tube in a vertical arc about the sleeve and trunnion, an elongate drilling guide cylinder mounted on the gear housing, an auger shaft mounted in the guide cylinder and extending through the housing, gearing in the gear case, a shaft in the torque tube operably connected with both gearings, and a second hy-

draulic cylinder mounted on the support and connected to the drilling guide cylinder for adjusting the gear housing and guide cylinder in a vertical arc about the torque tube and hanger transverse to the plane of adjustment by the first hydraulic cylinder.

3. In an earth auger, the combination of a portable support, a power plant mounted on the support, a gear case having a driven shaft connecting with the power plant, a sleeve enclosing the driven shaft and rotatably mounted on the support, said sleeve being connected to the gear case, a trunnion connected to the opposite side of the gear case, the case being supported on the sleeve and trunnion so as to be rotatable in an arc around the longitudinal axis of the driven shaft, a torque tube extending from said case, a gear housing connected to the extended end of said tube, a second trunnion connected to the opposite side of said housing, an upright standard carried on the rear of the support adjacent the second trunnion and having a flat rearward face, a hanger having a forwardly directed flat face slideably abutting the face on the standard, said hanger receiving the second trunnion on the gear housing, a hydraulic cylinder vertically secured to said standard and having a piston, a piston rod connected to the piston and extending from the cylinder, the extending end of the rod being pivotally connected with the hanger so as to move the hanger upwardly and downwardly to swing the housing and the guide cylinder in a vertical arc around the longitudinal axis of the sleeve and first trunnion, an elongate drilling guide cylinder mounted on the gear housing, an auger shaft mounted in the guide cylinder and extending through the housing, gearing in the housing for rotating said shaft, gearing in the gear case, a shaft in the torque tube operably connected with both gearings, and a second hydraulic cylinder mounted on the support and connected to the drilling guide cylinder for adjusting the gear housing and guide cylinder in a vertical arc about the torque tube and hanger transverse to the plane of adjustment by the first hydraulic cylinder.

JOHN C. JAQUES.
